United States Patent Office

Des. 193,772
Patented Oct. 9, 1962

193,772

UTILITY CART

Fredrick F. Brunette, Farmington, Mich., assignor to Brilliant Products Incorporated, Farmington, Mich., a corporation of Michigan

Filed Dec. 18, 1961, Ser. No. 67,954

Term of patent 14 years

(Cl. D14—3)

FIG. 1.

FIG. 2.

FIG. 1 is a perspective view of a utility cart showing my new design.

FIG. 2 is an end elevational view thereof.

The characteristic features of my design reside in the pair of tubular members forming the rear bumpers and load platform as best shown in FIG. 1.

I claim:

The ornamental design for a utility cart, as shown and described.
